UNITED STATES PATENT OFFICE.

E. ELLSWORTH PALMER, OF BARABOO, WISCONSIN.

DRESS-CHART.

SPECIFICATION forming part of Letters Patent No. 252,507, dated January 17, 1882.

Application filed October 8, 1881. (No model.)

To all whom it may concern:

Be it known that I, E. ELLSWORTH PALMER, of Baraboo, in the county of Sauk and State of Wisconsin, have invented certain new and useful Improvements in Dress-Charts; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan of the chart which designates the dress-waist and skirt-rule, and Fig. 2 is a plan of the sleeve-chart used with the former.

My invention has relation to charts for cutting out dress-patterns, which charts are provided with certain scales and other marks to regulate the size and proportion of the dresses to be cut from them; and it consists in an improved construction and marking of charts of that class, having for its object to simplify and facilitate their use, as hereinafter more fully set forth.

My improved plan or system as applied to dress-charts consists of only two separate charts, (designated respectively as Figs. 1 and 2 on the annexed sheet of drawings.)

Fig. 1 represents the chart for marking and cutting the pattern of the waist and skirt, and comprises a back waist-measure, (marked A,) a front waist-measure, (marked B,) and a dart-scale, (designated by the letter C.) On the opposite side or edge of the chart is the back shoulder-rule, (marked D,) and above that the front and back shoulder-rule, the cross basque dart rule and the side-form rule, (indicated by the letters E, F, and G, respectively.) At the top of the chart is the dart-rule H, and at the bot-

tom the skirt-rule I, while the neck-opening K is located between the skirt-rule and back shoulder-rule in the lower left-hand corner of the plan, as represented in Fig. 1 of the drawings. In the body of the chart are the scales and measures for taking the size, which enables the chart to be used for fitting any figure from that of a small child to a robust woman. The use of these measures is well understood and requires no further explanation.

In Fig. 2 I have shown a plan of the sleeve-chart for fitting and cutting the sleeve-pattern. The measure is taken from the middle line, (marked L,) along the scales on both edges of the chart, which is curved and tapers from its base M to a point, N, as clearly shown in the drawings.

I am aware of the Letters Patent No. 187,587, granted on February 20, 1877, to Lucy J. Bixby, for certain pattern-charts for cutting garments, and do not claim anything therein shown and claimed. The construction of the Bixby charts differs from mine in essential particulars and could not be used in the same manner as mine.

What I claim, and desire to secure by Letters Patent of the United States, is—

The pattern-charts herein shown and described, and denoted respectively Fig. 1 and Fig. 2, of the configuration shown, and provided with the series of measures, scales, and rules, arranged on the respective charts in the manner shown and described.

In testimony that I claim the foregoing as my own I have hereto affixed my signature in presence of two witnesses.

E. ELLSWORTH PALMER.
